PACKAGING CIGARS

Joseph A. Neumair, Hollis, N. Y., assignor to
International Cigar Machinery Company, a
corporation of New Jersey

Application May 22, 1937, Serial No. 144,210

4 Claims. (Cl. 93—2)

This invention relates to improvements in wrapping or enveloping machines, more particularly to the packaging of cigars and other articles wherein "Cellophane" or other similar wrapping material is used. The invention comprises an improved package, a method of making the same and an improvement on an existing form of cigar enveloping machine whereby my method may be carried out in the packaging of 10 various articles.

The main object of this invention is to enclose cigars within a sealed envelope having a suitably attached tear tab projecting therefrom to facilitate opening. To this end, in the particular embodiment of the invention illustrated herein the tear tabs are severed from a strip and secured to one margin of the wrapping material previous to envelopment of the cigar therein. Another object of the invention is to provide means for 20 holding the severed tear tab under pressure against the wrapping material to cause it to adhere to the adhesive or "Cellosolve" previously applied to the same. Still another object is to weaken, as by nicking, the outer seam edge of the wrapper length on one or both sides of the tear tab before the cigar is wrapped therein.

With these and other objects not specifically mentioned in view, the invention resides in certain methods, packages and constructions hereinafter more fully described and defined in the appended claims.

In the accompanying drawings which form a part of this specification and in which like characters of reference indicate the same or like parts:

Fig. 1 is a front elevation of a tear tab applying device constructed in accordance with my invention;

Figs. 2 and 3 are detail views of the front and side respectively of its driving mechanism;

Fig. 4 is a fragmentary view of the device showing the wrapper material being nicked at one side of the tear tab previously attached thereto;

Fig. 5 is a sectional view taken on the line 45 5—5 of Fig. 1;

Fig. 6 is a sectional view (taken on line 6—6 of Fig. 1) of the knife holder bracket and tear tab presser; and

Fig. 7 is a perspective view of a wrapped cigar 50 having a tear tab attached to its wrapper.

The particular embodiment of the invention selected for illustration is shown in conjunction with a cigar enveloping machine of the general type shown in the patent to H. H. Wheeler, No. 55 1,899,174, issued February 28, 1933.

Referring to Figs. 1, 2, 3 and 5 of the accompanying drawings, a tear tab strip T is fed from a reel R mounted on a shaft 10, loosely supported in bearings (not shown) of the main frame 11 of the cigar enveloping machine. The tear tab strip T is drawn from a reel R and over a guide roller 12 suitably pivoted at 13 on the frame 11 by the coaction of a feed roller 14 mounted on a shaft 15 supported in a bracket 16 with a feed roller 17 (Fig. 5). The latter is yieldingly held against 10 the feed roller 14, as will be presently described, thereby providing the requisite feeding tension on the tear tab strip. Arms 18 are provided with pintles 19 supporting the tension roller 17 and are mounted on a shaft 20 journaled in bearings 15 of bracket 16 (Fig. 5) and a bearing 21 of a bracket 22 (Fig. 2). Tension spring 18a anchored to the bracket 16 is connected to the arm 18 for suitably urging the feed roller 17 against the roller 14.

To the shaft 15 is fastened a ratchet 23 with which engages a pawl 24 carried by an oscillating gear 25 meshing with a vertically reciprocating rack 26 actuated by a wrapper feed control mechanism F such as disclosed in Patent No. 1,875,974. 25 Mechanism F is operated by a lever 27 from the main drive of the wrapping machine in the manner shown in said patent.

After passing the feed roller 14 the tear tab strip T is led through a channel 28 in a vertical 3 guide 29 attached to the bracket 16 (Figs. 1, 5 and 6). To the guide 29 is attached a knife holder bracket 30 on the lower end of which is mounted a stationary ledger plate 31. A knife blade 32 is pivotally mounted to swing on a stud 33 set in the lower end of the bracket 30. A torsion spring 34 (Fig. 1) anchored in the stud 33 urges the knife blade 32 against an adjustable operating screw 35 of the knife operating arm 36. The latter is pivoted to a stud 37 held by the 41 bracket 16 and is provided with an extension 38 carrying a cam roller 39 held in engagement with a cam 40 mounted on a shaft 41 by a spring 42 (Fig. 5). A sprocket 43 on the shaft 41 is driven by a chain 44 (Fig. 1) running over a drive 41 sprocket (not shown).

The tear tab strip T emerges vertically from the guide 29 and it is halted with its leading end in a position adjacent the upper edge of the web of Cellophane wrapper material W and in 50 front of it, as viewed in Fig. 1, which is the inner side of the wrapper. Here the desired length of tear tab T' is cut by coaction of the knife blades 31 and 32 when the knife operating arm 36 is swung down with the operating screw 35 to ac-

tuate the blade 32. While the tear tab T' is being cut, a pressure pad 45 yieldingly mounted on the knife operating arm 36 by means of a slidale bolt 46 around which a spring 47 is fitted holds 5 the tear tab T' prior to its severance against a portion of the wrapper web W previously coated with adhesive or "Cellosolve". In case coated "Cellophane" is used for the wrapper and tear tab material, "Cellosolve" may be applied to the 10 web W to cause the tear tab strip to adhere thereto. The nicking knives 48 (Fig. 6) cut into the outer seam edge of the Cellophane wrapper web W at 48a at either or both sides of the tear tab as shown, (Fig. 7) while the same is being 15 held (Fig. 3) by the pressure pad 45 against the adhesive applied previously at A (Fig. 1). The nicking at either or both sides of the tear tab T' will facilitate rupturing of wrapper as indicated in dot-and-dash lines at A. A paster or dauber 20 of any well-known construction (not shown) may be located at B to apply adhesive or "Cellosolve" to the web W.

The wrapper web W is fed from a reel R' supported on a stud 49 of frame 11, by a pair of feed 25 rollers 50 into horizontal guides 51 attached to the main frame 11 and cut off by a knife 52 which is operated from the main drive of the wrapping machine, in the manner shown in Patent #1,875,974. Bevel gear 53 on the feed roller shaft 30 54 meshes with bevel gear 55 mounted on a shaft 56 which is operated by the wrapper feed drive and control mechanism F whereby the feeding of the wrapper material is synchronized with the tear tab strip.

35 The cigars C which are to be wrapped are fed from a table 57 (Fig. 5) intermittently by pusher finger 58 to a pair of oscillating transfer arms 59 fixed to a shaft 60. The transfer arms 59 take one cigar C at a time and push it together with the 40 wrapper blank W to which has been affixed the tear tab T', into a turret pocket (not shown) thereby folding the wrapper about three sides of the cigar. Upon leaving station I of the turret the tabbed or outer seam edge of the wrapper 45 enfolding the cigar C indicated in dot and dash lines (Fig. 5) will be folded by a stationary plate 61, over the inner seam edge which has previously been folded inwardly by folder 62. After 50 enfolding of the cigar has been completed, a heating element 62' at station II engages and effectively seals the wrapper seam edges to each other and the portion of tear tab T' lying therebetween (Fig. 7).

If the wrapping material and tab material were

provided with a fusible coating they could be heat sealed to each other instead of adhesively secured. Instead of using coated transparent or translucent material, uncoated material of a cel- 5 lulosic or other nature may be used. For example if uncoated "Cellophane" were used it would be necessary to secure the tab to its margin by adhesive. Moreover, opaque material such as coated or uncoated foil may be used for the wrapping material

5

10

What is claimed is:

1. The combination with means for feeding a web of wrapping material, of a cutter for severing wrapper lengths from said web, members for feeding a web of tear tab material transversely 15 of the web of wrapping material and severing tear tabs therefrom of a length shorter than the width of the wrapper lengths, mechanism for securing the severed tear tabs to one margin of the wrapping material, and a device for lapping the 20 margins of the tabbed wrapper upon each other to envelope an article with a tab protruding from the seam so formed.

2. The combination with means for feeding a 25 web of wrapping material, of a cutter for severing wrapper lengths from said web, mechanism for securing tear tabs to one longitudinal margin only of the wrapping material, a device for lapping the longitudinal margins of the tabbed 30 wrapper upon each other to envelope an article with a tab protruding from the seam so formed, and a member for weakening the outer seam edge of the wrapping material adjacent the tabbed portion thereof.

3. The combination with means for feeding a 35 web of wrapping material, of a cutter for severing wrapper lengths from said web, mechanism for cutting and securing tear tabs of a length shorter than the width of the wrapper lengths to one margin only of the wrapping material, a device 40 for lapping the margins of the tabbed wrapper upon each other to envelope an article with a tab protruding from the seam so formed, and members for nicking the outer seam edge of the wrapper at either side of a tabbed portion thereof.

4. The combination with mechanism for securing 45 tear tabs of a length shorter than the width of wrapping material to the inner face of one longitudinal margin of the wrapping material, of means for lapping the longitudinal margins of the 50 tabbed wrapping material upon each other to envelope an article with a tab protruding from the seam so formed.

JOSEPH A. NEUMAIR.
